CLAIM

I claim the ornamental design for a make-up applicator, as shown and described.

DESCRIPTION

FIG. 1 is a perspective view of the make-up applicator showing my new design;

FIG. 2 is a front elevation thereof;

FIG. 3 is a top plan view thereof;

FIG. 4 is a right side elevation thereof;

FIG. 5 is a bottom plan view thereof;

FIG. 6 is a rear elevation thereof; and,

FIG. 7 is a left side elevation thereof.
